ABSTRACT

An automatic transporting apparatus for cigarettes which comprises receptacles circulating along an endless path having portions disposed in several vertical planes extending between one or more filling devices which fill the receptacles with blocks or groups of cigarettes and an evacuating device which evacuates the cigarettes from filled receptacles for introduction into a packaging machine. The cigarettes extend transversely of the bottom walls of the receptacles and the conveyor system of the transporting apparatus includes two superimposed storing units in one of which filled receptacles advance sideways toward the evacuating device in such a way that the cigarettes move axially. Empty receptacles move sideways through the other storing unit toward the filling device. The other storing unit is located above the one storing unit.

APPARATUS FOR TRANSPORTING RECEPTACLES

CROSS-REFERENCE TO RELATED CASES

This is a continuation of our copending application Ser. No. 30,204, filed Apr. 20, 1970 now abandoned, which is a division of our application Ser. No. 631,504, filed Apr. 17, 1967 and now abandoned.

A machine for filling multi-cell receptacles is disclosed in U.S. Pat. No. 3,444,981 granted May 20, 1969 to Schubert and assigned to the same assignee.

BACKGROUND OF THE INVENTION

The present invention relates to automatic manufacturing and packaging plants for non-filter cigarettes, filter cigarettes, filter rods, non-filter cigars, filter cigars, non-filter cigarillos, filter cigarillos and analogous rod-shaped articles. More particularly, the invention relates to improvements in an apparatus which can be utilized to transport a supply of receptacles (also called trays or chargers) between one or more filling devices where the receptacles are filled with cigarettes or other rod-shaped articles and an evacuating device which removes articles from filled receptacles and feeds them into one or more packaging or other processing machines. Still more particularly, the invention relates to improvements in transporting apparatus which may be utilized with advantage in the formation and transportation of blocks of accurately arrayed cigarettes or analogous rod-shaped articles, for example, to transfer blocks of twenty cigarettes each from one or more makers to a packaging machine.

SUMMARY OF THE INVENTION

It is an object of our invention to provide an automatic manufacturing and packaging plant for rod-shaped articles, particularly for cigarettes or filter cigarettes, wherein the articles can be assembled into blocks and fed to a packaging machine in a small area and in rapid sequence to meet the requirements of modern high-speed packaging or other processing machines.

Another object of the invention is to provide the manufacturing plant with a novel transporting apparatus which can transfer large numbers of blocks with requisite accuracy, without any damage to the articles, and without changing the distribution of such articles in the blocks.

A further object of our invention is to provide the transporting apparatus with a novel system of conveyors and to assemble the transporting apparatus in such a way that it can be readily combined with or incorporated in known tray-filling and tray-evacuating machines.

An additional object of the invention is to provide a transporting apparatus whose conveyors can support and store a large number of empty and filled receptacles in a small area and in such a way that empty receptacles can be automatically fed to one or more filling machines while the evacuating machine or machines always receive a succession of filled receptacles.

Still another object of the instant invention is to provide a manufacturing and packaging plant for cigarettes or like rod-shaped articles which can store larger quantities of properly arrayed articles while occupying

the same or a smaller floor space than presently known plants of such character.

The invention is embodied in an automatic manufacturing and packaging plant for cigarettes, filter cigarettes, filter rods, filter cigars or analogous rod-shaped articles which are transported in receptacles or chargers having elongated bottom walls. The plant comprises at least one filling device having transfer means for introducing articles into empty receptacles to thus convert such receptacles into filled receptacles wherein the articles extend at right angles to the longitudinal directions of the respective bottom walls, means (for example, one or more machines for the production of plain or filter cigarettes) for supplying articles to the filling device, an evacuating device having means for evacuating articles from filled receptacles to thus convert such receptacles into empty receptacles, consuming means (e.g., one or more packaging machines) arranged to receive articles from the evacuating device, and conveyor means for circulating empty and filled receptacles along an endless path, including first and second storing means common to the filling and evacuating devices and respectively arranged to accommodate supplies of empty and filled receptacles, and means for moving the receptacles through the storing means in such orientation that the respective bottom walls travel sideways.

One of the storing means is preferably located at a level above the other storing means.

The novel features which are considered as characteristic of the invention are set forth in particular in the appended claims. The improved transporting apparatus itself, however, both as to its construction and its mode of operation, together with additional features and advantages thereof, will be best understood upon perusal of the following detailed description of certain specific embodiments with reference to the accompanying drawing.

BRIEF DESCRIPTION OF THE DRAWING

FIG. 1 is a schematic top plan view of an automatic manufacturing and processing plant for filter cigarettes including a transporting apparatus which embodies one form of our invention;

FIG. 2 is an enlarged fragmentary perspective view of a portion of the transporting apparatus, substantially as seen in the direction of arrow II in FIG. 1;

FIG. 3 is an enlarged fragmentary perspective view of a portion of the transporting apparatus substantially as seen in the direction of arrow III in FIG. 1;

FIG. 4 is an enlarged side elevation view of a portion of the transporting apparatus as seen in the direction of arrow IV in FIG. 3;

FIG. 5 is an enlarged side elevational view as seen in the direction of arrow V in FIG. 3;

FIG. 6 is a greatly simplified perspective view of the structure shown in FIG. 3 and illustrates the path of movement of filled and empty receptacles between one of the filling devices and the evacuating device; and

FIG. 7 is a similar perspective view illustrating the path of movement of receptacles in an automatic manufacturing and processing plant which comprises a single filling device.

DESCRIPTION OF THE PREFERRED EMBODIMENTS

Referring first to FIG. 1, the improved transporting

apparatus couples two filling devices or machines 2, 4 with an evacuating device or machine 6 and is installed in a plant or production line for automatic manufacture, packaging and further processing of filter cigarettes. The transporting apparatus comprises two superimposed parallel straight horizontal main conveyors 8 and 10 which respectively constitute storing units for empty and filled receptacles and form part of a conveyor system which transports the receptacles along an endless path. The filling machines 2 and 4 are accommodated at two spaced filling stations and respectively receive filter cigarettes from two filter cigarette producing machines or makers 12 and 14, and these makers respectively receive non-filter cigarettes from two cigarette making machines 16 and 18. The evacuating machine 6 occupies an evacuating station behind the main conveyors 8 and 10 and is combined with the transporting apparatus and with a packaging machine 20 which provides blocks of accurately arrayed filter cigarettes with inner and outer wrappers. The packs issuing from the packaging machine 20 are fed into a wrapping machine 22 which provides each pack with a transparent plastic envelope, and the thus wrapped packs are thereupon fed into a bunching machine 24 which assembles predetermined numbers of packs into bunches, and such bunches are then received and transported by a take-off conveyor 26. The transporting apparatus which includes the main conveyors 8 and 10 is capable of supplying to the evacuating machine 6 the combined output of both filling machines 2 and 4. Its details are shown in FIGS. 2 to 5.

The two filling machines 2, 4 are of identical construction and are mirror symmetrical with reference to each other. Each of these machines comprises a suction head or collector 28 which picks up filter cigarettes 30 from a supply conveyor 32 (also called catcher band) carrying the output of the respective maker 12 or 14. The collector 28 assembles successive layers each of which contains a predetermined number of filter cigarettes 30. Each such layer is then transformed into ten coplanar rows containing six or seven cigarettes each, it being assumed that the packaging machine 20 is arranged to receive blocks 160 (see FIG. 5) of twenty cigarettes each in the usual array, namely two outer rows of seven cigarettes each and a median row of six cigarettes whose cigarettes are staggered transversely with reference to the cigarettes of the two outer rows. The manner in which the collector 28 can pick up a single layer and converts it into a predetermined number of coplanar rows is disclosed, for example, in the aforementioned copending application Ser. No. 559,538 of Schubert. The collector 28 cooperates with a first transfer member 34 which resembles a flat plate-like body and is provided with a row of ten coplanar pushers 34a each of which can shift a row of filter cigarettes 30 from the flutes at the underside of the collector 28 into a multi-cell receptacle or charger 38 which is located directly behind the collector. The charger 38 has several superimposed parallel rows of ten cells 36 each, and one such row registers with the pushers 34a when the transfer member 34 performs a working stroke and moves ten rows of six or seven cigarettes each axially toward the charger 38. The transporting apparatus comprises two rotary drum-shaped conveyors 40 of each of which is located behind one of the collectors 28 and serves to move the respective charger 38 downwardly in stepwise fashion so that a row of cells 36 is

always ready to receive a row of filter cigarettes 30 when the respective transfer member 34 performs a working stroke.

Each drum 40 is indexed in synchronism with the 5 operation of the respective transfer member 34 and cooperates with the horizontal partitions 38a of the adjoining charger 38. The chargers have bottom walls 38b whose length exceeds their width and the cigarettes 30 which enter the cells 36 extend transversely of such 10 bottom walls. The chargers 38 can be said to constitute racks and the drums 40 constitute pinions which mesh with the respective chargers to lower them stepwise behind the associated collectors 28. Each drum 40 is rotated intermittently by an indexing mechanism 42. A 15 vertically movable conveyor or platform 44 (FIGS. 3 and 4) is provided below and forwardly of each drum 40, and each of these platforms 44 is raised and lowered by a drive mechanism including a pneumatic cylinder and piston unit (not shown) which rocks a lever 20 connected to a shaft 46, the latter carrying two links 48 coupled to the respective side walls of the platform 44. Two additional links 52 are connected to the lower portions of such side walls and are articulately connected to the upper links 48 by elongated connecting rods 50. 25 The links 52 can rock about a fixed horizontal shaft 46a located at a level below the shaft 46. As clearly shown in FIG. 4, the drive mechanism 46-52 can raise or lower the chargers 38 and can also move the chargers rearwardly (see the phantom line 44A) without changing the inclination of the chargers. The just described 30 drive mechanism can transfer filled chargers onto a horizontal conveyor table 54 which is located at a level below the respective drum 40. The table 54 serves as a means for guiding and supporting filled chargers 35 when such chargers travel in the lowermost portions of their paths on the way toward the evacuating machine 6. The transporting apparatus comprises two lower auxiliary conveyors 56 which serve to move filled chargers 38 sideways as indicated in FIG. 1 by arrows 2A and 4A. Each conveyor 56 comprises ways 58 and an 40 endless chain provided with motion transmitting lugs 57. Each chain is driven by a motor 60 which is started by an electric switch 62 located at a level above the respective table 54 and actuatable by successive filled chargers 38. The upper stringers of the endless chains of the auxiliary conveyors 56 advance filled chargers 38 toward a junction in the transporting apparatus at which the filled chargers begin to advance rearwardly 45 and away from the filling machines 2, 4 in a direction toward the evacuating machine 6. The just mentioned junction accommodates a shuffling platform 64 and a shifting member 66 which is operated by a crank drive (not shown). The lower main conveyor 10 of the transporting apparatus comprises two flexible elements here 50 shown as bands 68, 70 which serve to advance filled chargers 36 sideways in the direction indicated in FIG. 1 by arrow 6A. During such advance of chargers 38, the cigarettes 30 move axially or lengthwise. Electric switches 72 are installed below the discharge ends of auxiliary conveyors 56 close to the shuffling platform 64. These switches can be operated by actuating members or trips 74 on the lugs 57 of the respective auxiliary conveyors 56. The trips 74 and switches 72 perform the dual function of arresting the motors 60 of the respective auxiliary conveyors 56 and of simultaneously 55 starting the drive for the shifting member 66. The shuffling platform 64 supports an electric switch 76 which 60 65

is actuated by the shifting member 66 and is connected in series with the electric switches 62. The position of one of the switches 62 is best shown in FIG. 4 and it will be noted that this switch is actuated by a filled charger 38 when the latter is pushed onto the respective ways 58 so that it is ready to be transported by the respective auxiliary conveyor 56.

The discharge ends of the bands 68, 70 are located in front of the evacuating machine 6 and deliver successive filled chargers 38 into the range of an elevating device including vertically reciprocable conveyor or platform 78 best shown in FIG. 5. This platform 78 serves to lift filled chargers 38 into the range of a further drum-shaped conveyor or pinion 80 whose operation is analogous to that of the drums 40 and which is indexable to lift the chargers 38 stepwise during evacuation of cigarette blocks 160 from the rows of cells 36. The drum 80 is indexed in synchronism with the operation of a second reciprocable transfer member 82 which comprises 10 coplanar plungers 84 each of which can evacuate the contents of an entire cell 36, i.e. each plunger 84 can expel from a charger 38 a complete block 160 of twenty filter cigarettes 30 at a time. The drive which reciprocates the transfer member 82 includes a cam shaft 96 which rotates a disk-shaped cam 94 cooperating with a roller follower 92 provided on the lower arm of a two-armed lever 90. The upper arm of the lever 90 is connected to a rod 88 which rocks a lever 86, the latter being connected with the transfer member 82. The just described parts 86-96 cause the transfer member 82 to perform working strokes and the drive further includes a suitable spring which is attached to the lever 90 to bias the follower 92 against the face of the cam 94 so that the transfer member 82 performs a return stroke whenever the follower 92 moves nearer to the axis of the cam shaft 96. The transfer member 82 forms part of the evacuating machine 6 which latter further includes an endless flexible conveyor 98 comprising two endless link chains and a series of transversely extending open-ended pockets 100 connected to such endless chains. The conveyor 98 is driven intermittently by a sprocket 102 in such a way that ten empty pockets 100 register with ten filled cells 36 of a charger 38 which is engaged by the drum 80 when the transfer member 82 performs a working stroke whereby the plungers 84 transfer ten blocks 160 of filter cigarettes 30 into such empty pockets.

A further transfer member 106 having two plungers 107 (see the upper left-hand portion of FIG. 3) forms part of the packaging machine 20 and serves to expel blocks 160 from filled pockets 100. Such blocks are introduced into hollow mandrels 104a of a conventional turret 104 which accommodate blocks 160 of twenty cigarettes each while the machine 20 wraps the blocks into inner and outer wrappers in a manner not forming part of the present invention. The evacuating machine 6 further comprises a stationary mouthpiece 108 with ten coplanar channels which guide the blocks 160 during transfer from cells 36 into the registering pockets 100.

The transporting apparatus of our invention further comprises a displacing conveyor or device 110 which transfers empty chargers 38 onto the endless flexible elements or bands 130, 132 of the upper main conveyor 8, the latter serving to move such empty chargers sideways toward but at a level above the shuffling platform 64. The displacing device 110 is guided in bear-

ings 112 shown in the upper part of FIG. 3 and in FIG. 5, and the drive for reciprocating the device 110 comprises a pneumatic cylinder and piston unit 114.

The sprocket 102 for the chains of the flexible conveyor 98 is driven by a shaft 103 which is operatively connected with the indexing mechanism for the drum 80 and with the cam shaft 96 and operates in synchronism with the drive for the packaging machine 20, i.e., with the drive for the third transfer member 106. The arrangement is such that the conveyor 98 is advanced by five steps each of which corresponds to twice the distance between the centers of two adjoining pockets 100 during each interval when the transfer member 82 dwells in retracted position. The transfer member 106 performs a working stroke during each interval between two successive steps of the conveyor 98 whereby the plungers 107 transfer two blocks 160 of twenty cigarettes 30 each into the registering empty mandrels 104a of the turret 104. Upon completion of each fifth step, 10 empty pockets 100 register with a row of 10 filled cells 36 in that charger 38 which is engaged by the drum 80, and the transfer member 82 then performs a rapidly executed working stroke so that its plungers 84 transfer ten blocks 160 into the registering pockets 100. The blocks 160 are caused to pass through the corresponding channels of the mouthpiece 108.

The housing or frame 116 of the evacuating machine 6 carries three electric switches 118, 120, 122 which are adjacent to the path of movement of the platform 78 (see FIG. 5). The platform 78 carries an actuating member or trip 124 which can operate the switch 118, the latter serving to start the drive for the endless band 68, 70 of the lower main conveyor 10. The switch 120 is operated by the foremost filled charger 38 on the bands 68, 70 and serves to arrest the just mentioned drive for the bands 68, 70. At the same time, the switch 122 starts the drive for the platform 78 so the platform moves upwardly and advances the filled charger 38 into the range of the drum 80. The drive for the platform 78 comprises a pneumatic cylinder and piston unit which is not shown in the drawings. The switch 122 is operated by a filled charger 38 on the platform 78 or by the platform itself and serves to reverse the drive for this platform when the respective filled charger reaches the drum 80 whereby the platform 78 descends to its lower end position and is ready to receive a fresh filled charger 38 from the bands 68, 70.

The aforementioned housing or frame 116 of the evacuating machine 6 further carries an electric switch 128 which is mounted on a supporting bracket 126 and is operated by an empty charger 38 when such charger reaches its upper end position. The empty charger is moved to such upper end position by the drum 80. The switch 128 causes the cylinder and piston unit 114 to perform a working stroke (in a direction to the left, as viewed in FIG. 5) whereby the displacing display 110 transfers the respective empty charger onto the upper runs of endless bands 130, 132 which form part of the aforementioned upper main conveyor 8.

As stated before, the bands 130, 132 will transport empty chargers 38 back in a direction toward the shuffling platform 64. The bands 130, 132 deliver empty chargers onto a distributor platform 134 which distributes empty chargers to two upper auxiliary conveyors 136 each having an endless chain provided with motion transmitting lugs 138. The function of the auxiliary

conveyors 136 is just the opposite of that of the lower auxiliary conveyors 56, i.e., they advance empty chargers back toward the corresponding filling machines 2, 4. The auxiliary conveyors 136 deliver empty chargers onto tables 140 each cooperating with an advancing member 142 and carrying a pair of endless conveyor bands 144, 146. The distributor platform 134 carries an electric switch 148 which is actuated by empty chargers 38 to start and arrest the drive for the bands 130, 132 of the upper main conveyor 8 as well as to start the drive for one of the auxiliary conveyors 136 in the one or the other direction. Two additional electric switches 150 are provided on the distributor platform 134 adjacent to the ends of the auxiliary conveyors 136 and each of these switches is actuatable by trips 152 provided on the lugs 138 of the respective conveyor 136. The switches 150 arrest the respective conveyors 136 and start the drives for the associated advancing members 142. Each table 140 carries an electric selector switch 154 having a movable contact provided with a roller which extends above the surface of the table 140. When an empty charger 38 rests on the roller of the adjacent switch 154, the latter arrests the drive for the corresponding auxiliary conveyor 136. When the empty charger is moved off the respective switch 154, the latter starts the drive for the corresponding auxiliary conveyor 136 so that such conveyor advances empty chargers toward the respective drum 40. At a level above the tables 140, there are provided electric switches 158 which are mounted on supporting brackets 156. The switches 158 are actuated by empty chargers 38 to start and arrest the drives for the bands 144, 146.

The operation is as follows:

The machines 2 and 4 fill successive chargers 38 in a manner as disclosed in the aforementioned copending application Ser. No. 559,538 of Schubert. Thus, the pushers 34a of the transfer member 34 shift successively assembled rows of filter cigarettes 30 in the axial direction of such cigarettes whereby the cigarettes leave the flutes of the corresponding collectors 28 and enter the registering cells 36. The operation of each transfer member 34 is synchronized with operation of the respective collector 28 and the latter assembles, successively, 10 rows of seven cigarettes each, 10 rows of six cigarettes each, and ten rows of seven cigarettes each so that the cells 36 receive blocks 160 each of which contains two outer rows of seven cigarettes each and a median row of six cigarettes in an array which is customary in cigarette packs. The drive for the transfer member 34 controls the operation of the indexing mechanism 42 for the corresponding drum 40 so that the latter lowers the charger 38 in stepwise fashion. The axially parallel ribs of the drum 40 act not unlike the teeth of a pinion and cooperate with the horizontal partitions 38a of the adjoining empty or partially filled charger 38 to lower the latter at intervals determined by the associated transfer member 34. Each third angular displacement of the drum 40 is greater than the preceding two to account for the thickness of partitions 38a.

When a charger 38 is filled, i.e., when each of the uppermost row of its cells 36 has received a third or uppermost row of filter cigarettes 30, the bottom wall 38b of such filled charger comes to rest on the corresponding platform 44 which latter is then held in its uppermost position. A suitable pressure-responsive valve

(not shown) is actuated by the filled charger 38 and operates the pneumatic cylinder and piston unit which rotates or permits rotation of the shaft 46 in a counter-clockwise direction, as viewed in FIG. 3, so that the platform 44 travels along the arcuate path 44A shown in FIG. 4 and transfers the filled charger 38 onto the corresponding table 54. The cylinder and piston unit of the drive for the platform 44 is preferably of the double-acting type so that it can rotate the shaft 46 in two directions. As clearly shown in FIG. 4, the parts 48-52 can move a filled charger 38 downwardly and rearwardly so that a charger which comes to rest on the table 54 does not interfere with stepwise descent of a partially filled charger which is engaged by the drum 40. As the platform 44 deposits a filled charger 38 onto the table 54, it simultaneously pushes a column of filled chargers 38 along the table 54 so that the rearmost filled charger advances onto the associated ways 58 and is in the path of lugs 57 on the corresponding auxiliary conveyor 56. Such rearmost charger 38 also actuates the switch 62 which starts the motor 60 so that the auxiliary conveyor 56 advances the filled charger along the ways 58 and toward the shuffling platform 64. When the platform 44 reaches its lower end position, it resets the aforementioned valve so that the pneumatic cylinder and piston unit operates in reverse and returns the platform 44 to the upper end position shown in FIG. 4. This platform is then ready to receive the next-following filled charger 38.

When a filled charger 38 reaches the shuffling platform 64, the trip 74 of the lug 57 which has pushed such filled charger along the ways 58 actuates the corresponding switch 72 which arrests the motor 60 for the auxiliary conveyor 56 and starts the drive for the shifting member 66 so that the latter performs a working stroke and pushes the rearmost filled charger of the column on the platform 64 onto the receiving ends of the endless bands 68, 70. The drive for the shifting member 66 is operatively connected with both motors 60 in such a way that the shifting member 66 is free to perform a working stroke only when the motors 60 are idle. This prevents collision of filled chargers 38 on the shuffling platform 64.

Upon completion of a working stroke, the shifting member 66 immediately returns to retracted position and actuates the switch 76 whose contacts are connected in series with the two switches 62 and which selects the circuits of the motors 60.

The two auxiliary conveyors 56 operate in two parallel planes so that chargers which were filled by the machine 2 are transferred onto the shuffling platform 64 behind chargers which were filled by the machine 4. In other words, a filled charger 38 coming in a direction from the machine 2 is more distant from the shifting member 66 (when the latter is moved to retracted position) than a charger 38 which has been filled by the machine 4.

The bands 68, 70 advance filled chargers 38 toward the evacuating machine 6 and the blocks 160 are evacuated by the transfer member 82. The discharge ends of the bands 68, 70 deliver successive filled chargers 38 onto the platform 78 (FIG. 5). Actually, the rearmost filled charger 38 is transferred onto the platform 78 by the next-following filled charger whenever the bands 68, 70 advance by a step in the direction indicated in FIG. 1 by the arrow 6A. A filled charger 38 which has been transferred onto the platform 78 actuates the

switch 120 which arrests the drive for the bands 68, 70 and energizes the solenoid of an electromagnetic valve (not shown) for the pneumatic cylinder and piston unit which lifts the platform 78. The upwardly moving platform 78 advances the filled charger 38 into abutment with the partially evacuated charger thereabove and continues to move the filled charger upwardly until the latter enters the range of and is engaged by the drum 80. The platform 78 is moved downwardly when the charger 38 on the platform 78 releases the switch 122. The indexing movements of the drum 80 are greater than those of the drums 40 because the drum 80 must lift a charger 38 by steps corresponding to the distance between the centers of two superimposed cells 36. As explained above, the plungers 84 of the second transfer member 82 transfer a full row of blocks 160 at a time, i.e., the transfer member 82 will perform a single working stroke while the transfer member 34 completes three working strokes. The operation of the transfer member 82 is synchronized with the operation of drum 80 in such a way that the plungers 84 transfer a row of blocks 160 into the registering pockets 100 of the flexible conveyor 98 while the charger 38 dwells between two successive stepwise advances in response to indexing of the drum 80. Blocks 160 which are transferred by the plungers 84 travel through the channels of the mouthpiece 108 and come to rest in the registering pockets 100. As stated before, the sprocket 102 advances the conveyor 98 by five steps in response to a single indexing movement of the drum 80, and each such step corresponds to twice the distance between the centers of two adjoining pockets 100 so that the conveyor 98 maintains ten empty pockets 100 in registry with the mouthpiece 108 whenever the transfer member 82 begins a working stroke to expel ten blocks 160 from a row of cells 36 in that charger 38 which is engaged by the drum 80. The transfer member 106 of the packaging machine 20 causes its plungers 107 to transfer two blocks 160 from the registering pockets 100 into the corresponding mandrels 104a of the turret 104 during each interval between successive stepwise advances of the flexible conveyor 98.

When the drum 80 takes over a filled charger 38 from the platform 78, such filled charger 38 begins to move upwardly in response to indexing of the drum 80 and the switch 122 then reverses the drive for the platform 78 and causes the latter to return to the lower end position. When the platform 78 reaches such lower end position, its trip 124 actuates the switch 118 which arrests the drive for the platform 78 and simultaneously starts the drive for the bands 68, 70 of the lower main conveyor 10 so that the bands advance a fresh filled charger 38 onto the platform 78. Such filled charger actuates the switch 120 and the procedure is repeated in the aforesigned sequence.

When the plungers 84 of the transfer member 82 have completed the transfer of blocks 160 from the lowermost row of cells 36 in a charger which is engaged by the drum 80, the thus emptied charger 38 assumes the phantom-line position shown in FIG. 5 and actuates the switch 128 which energizes the solenoid of a valve in the circuit of the drive 114 for the displacing device 110. This device 110 performs a single working stroke and transfers the empty charger onto the bands 130, 132 of the upper main conveyor 8. Such transfer of an empty charger 38 onto the bands 130, 132 need not necessarily start the drive for these bands.

When one of the upper auxiliary conveyors 136 advances an empty charger from the distributor platform 134 toward the corresponding table 140 to such an extent that the thus advanced charger moves off the roller of the switch 148 on the platform 134, the latter starts the drive for the bands 130, 132 of the main conveyor 8 and the bands continue to advance the empty charger which has been transferred by the displacing device 110 until such empty charger comes to rest on the switch 148 and thereby arrests the drive for the bands 130, 132. Of course, the bands 130, 132 may support an entire row or column of empty chargers so that they will advance only by a step in order to transfer an empty charger onto the platform 134 and to actuate the switch 148.

An empty charger 38 which rests on the switch 148 remains in such position until one of the filling machines 2, 4 sends a signal that it requires an empty charger. Such signal is transmitted by the corresponding selector switch 154 which the bands 144, 146 advance the column of empty chargers on the corresponding table 140 by a step so that the corresponding auxiliary conveyor 136 can deliver an empty charger from the distributor platform 134. For example, and if the switch 154 on the table 140 which is adjacent to the filling machine 2 sends a signal that the auxiliary conveyor 136 can advance an empty charger from the distributor platform 134 toward the table 140, one lug 138 of such auxiliary conveyor 136 advances the registering empty charger along the upper stringer of the auxiliary conveyor 136 and toward the table 140 behind the machine 2. The trip 152 of the lug 138 then actuates the switch 150 which arrests the drive for the auxiliary conveyor 136 and starts the drive for the adjoining advancing member 142. The member 142 performs a single working stroke toward the machine 2 and transfers the freshly delivered empty charger 38 onto the switch 154 whereby the latter blocks the drive for the auxiliary conveyor 136 so that the latter cannot transfer another empty charger until after the preceding empty charger moves off the switch 154. However, the auxiliary conveyor 136 can be driven in the opposite direction to return its lug 138 into a receiving position with reference to an empty charger on the distributor platform 134.

When the drum 40 behind the machine 2 has lowered a charger 38 to such an extent that this charger descends to a level below the corresponding switch 156, the latter starts the drive for the bands 144, 146 so that these bands advance an empty charger into registry with the descending charger. The thus advanced empty charger releases the switch 154 which releases or unblocks the drive of the associated auxiliary conveyor 136 so that the latter can remove an empty charger from the distributor platform 134 unless the other auxiliary conveyor has received a signal to deliver an empty charger to the machine 4.

As the bands 144, 146 advance an empty charger 38 toward the rear side of the machine 2, such empty charger actuates the switch 158 which then arrests the drive for the bands 144, 146. This empty charger then shares stepwise movements of the preceding charger which is still engaged by the adjoining drum 40. When the preceding charger is filled, the empty charger is positively engaged by the drum 40 and is thereupon lowered stepwise in a manner as described above. The empty charger exerts pressure on the filled charger below it so that such filled charger bears against the platform 44 (FIG.

4) and the platform actuates the aforementioned pressure-responsive switch which causes the drive for the platform 44 to transfer the filled charger onto the corresponding table 54.

Of course, the construction of the improved transporting apparatus can be simplified considerably if the evacuating machine 6 receives the output of a single filling machine 2 or 4. The chargers 38 then circulate in an endless path which is located in a single vertical plane in contrast to the apparatus of FIGS. 1 to 5 wherein chargers travelling between the machine 6 and the machine 2 or 4 travel in three mutually inclined vertical planes, namely, in a first plane which is defined by the main conveyors 8, 10 the platform 78, drum 80 and the displacing device 110, a second plane which is defined by auxiliary conveyors 56, 136, and a third plane defined by the bands 144, 146, drum 40, platform 44 and table 54. During travel in the first and third planes, the cigarettes 30 move axially. When travelling in the second plane, the cigarettes 30 move sideways. The manner in which the chargers 38 travel between the filling machine 4 and the evacuating machine 6 is illustrated schematically in FIG. 6. The arrow 200 indicates the direction of travel of empty, partially filled and filled chargers 38 with the drum 40 and platform 44. The arrow 201 indicates the direction of travel of filled chargers 38 along the table 54, and the arrow 202 indicates the direction of travel of filled chargers with the lower auxiliary conveyor 56. During travel with the bands 68, 70 of the lower main conveyor 10, filled chargers 38 advance in the direction of arrow 203, and the arrow 204 indicates the direction of travel of filled, partially filled and empty trays with the platform 78 and drum 80. The arrow 205 shows the direction of travel of empty chargers with the displacing member 110, bands 130, 132 of the upper main conveyor 8 and on the distributor platform 134. The arrow 206 indicates the direction of travel of empty chargers with the upper auxiliary conveyor 136, and the arrow 207 shows the direction of travel of an empty charger with the bands 144, 146 on the table 140. The arrows 200, 201 and 207 are located in a first vertical plane 210; the arrows 202, 206 are located in a second vertical plane 211; and the arrows 203, 204, 205 are located in a third vertical plane 212. In the illustrated embodiment, the planes 210, 212 make right angles with the plane 211.

FIG. 7 illustrates schematically a transporting apparatus which can transfer empty and filled receptacles or chargers between a single filling machine 2' and a single evacuating machine 6'. The arrow 300 indicates the direction of travel of empty chargers with the drum 40 and platform 44 which latter then transfers filled chargers directly onto the bands 68, 70 of the lower main conveyor 10 whereon filled chargers advance in the direction indicated by arrow 301. The arrow 302 indicates the direction of travel of filled, partially filled and empty chargers with the platform 78 and drum 80. The arrow 303 indicates the direction of travel of empty chargers with the bands 130, 132 of the upper main conveyor 8 which latter delivers empty chargers directly into the range of the drum 40. It will be seen that the arrows 300-303 are located in a single vertical plane 304. During travel in the plane 304, the cigarettes move axially or lengthwise.

Without further analysis, the foregoing will so fully reveal the gist of the present invention that others can,

by applying current knowledge, readily adapt it for various applications without omitting features which fairly constitute essential characteristics of the generic and specific aspects of our contribution to the art and, therefore, such adaptations should and are intended to be comprehended within the meaning and range of equivalence of the claims.

What is claimed as new and desired to be protected by Letters Patent is:

10. 1. In an automatic manufacuring and packaging plant for cigarettes or similar rod-shaped articles which are transported in receptacles having elongated bottom walls, a combination comprising at least one filling device having transfer means for introducing articles into empty receptacles to thus convert such receptacles into filled receptacles wherein the articles are disposed at right angles to the longitudinal directions of the respective bottom walls; means for supplying articles to said filling device; an evacuating device having means for evacuating articles from filled receptacles to thus convert such receptacles into empty receptacles; consuming means arranged to receive the thus evacuated articles; and conveyor means for circulating empty and filled receptacles along an endless path, including first and second storing means common to said devices and respectively arranged to accommodate supplies of empty and filled receptacles, and first and second means for respectively moving empty and filled receptacles through said first and second storing means on to said filling and evacuating devices respectively in such orientation that the respective bottom walls travel sideways and as long as said first and second storing means respectively contain empty and filled receptacles irrespective of the positions of such receptacles in the respective storing means.
2. A combination as defined in claim 1, wherein said transfer means comprises means for introducing groups of articles into empty receptacles.
3. A combination as defined in claim 1, wherein one of said storing means is located at a level above the other storing means.
4. A combination as defined in claim 1, wherein the means for moving the articles through said storing means comprises endless flexible elements.
45. 5. A combination as defined in claim 1 wherein said means for moving the receptacles through said storing means is arranged to move such receptacles along substantially horizontal paths which are at least substantially parallel to each other.
50. 6. A combination as defined in claim 1, wherein said means for supplying articles to said filling device comprises a plurality of producing machines.
55. 7. A combination as defined in claim 1, wherein said conveyor means comprises at least one portion which transports receptacles between different levels.
60. 8. In an automatic manufacturing and packaging plant for cigarettes or analogous rod-shaped articles which are transported in receptacles having elongated bottom walls, a combination comprising at least one filling device having transfer means for introducing articles into empty receptacles to thus convert such receptacles into filled receptacles wherein the articles are disposed at right angles to the longitudinal directions of the respective bottom walls; an evacuating device remote from said filling device and having means for removing articles from filled receptacles to thus convert such receptacles into empty receptacles; consuming

means arranged to receive articles which are removed from filled receptacles; first storing means disposed between said filling and evacuating devices and arranged to accommodate a supply of empty receptacles; second storing means disposed between said filling and evacuating devices and arranged to accommodate a supply of filled receptacles, said first and second storing means spanning at least a substantial part of the distance between said filling and evacuating devices and one of said storing means being located at a level above the other storing means, said removing and transfer means being each located at a level other than at least one of said storing means, said first and second storing means respectively comprising at least one first and at least one second conveyor respectively arranged to transport empty and filled receptacles in such positions that the bottom walls of the receptacles expend transversely of the direction of movement of the respective conveyors, said first and second conveyors being respectively arranged to furnish, when needed, to said filling and evacuating devices an empty and a filled receptacle as long as the first and second storing means respectively contain at least one empty and at least one filled receptacle irrespective of the initial position of such one receptacle in the respective storing means; first transporting means for moving empty receptacles delivered by said first conveyor along said transfer means and thereupon to said second storing means, said first transport-

ing means including conveyor means actuatable to transport receptacles from the level of said first storing means to the level of said filling means and thereupon to the level of said second storing means; second transporting means for moving filled receptacles delivered by said second conveyor to the removing means of said evacuating device and thereupon to said first conveyor, said second transporting means including conveyor means actuatable to move receptacles from the level of said second storing means to the level of said removing means and thereupon to the level of said first storing means; and first and second control means respectively located in the region of said filling and evacuating devices for respectively actuating the conveyor means of said first and second transporting means.

9. A combination as defined in claim 8, wherein said first and second conveyors are arranged to transport empty and filled receptacles along substantially horizontal paths, said conveyor means of said first and second transporting means including means for moving empty and filled receptacles along substantially vertical paths.

10. A combination as defined in claim 8, wherein each of said first and second conveyors comprises at least one endless flexible element having an upper stretch for supporting and moving the receptacles in the respective storing means.

UNITED STATES PATENT AND TRADEMARK OFFICE
Certificate

Patent No. 3,820,671

Patented June 28, 1974

Bernhard Schubert and Dietrich Bardenhagen

Application having been made by Bernhard Schubert and Dietrich Bardenhagen, the inventors named in the patent above identified, and Hauni-Werke Korber & Co. K.G. Hamburg-Bergedorf, Germany, the assignee, for the issuance of a certificate under the provisions of Title 35, Section 256, of the United States Code, deleting the name of Dietrich Bardenhagen as a joint inventor, and a showing and proof of facts satisfying the requirements of the said section having been submitted, it is this 2nd day of March 1976, certified that the name of the said Dietrich Bardenhagen is hereby deleted to the said patent as a joint inventor with the said Bernhard Schubert.

FRED W. SHERLING,
Associate Solicitor,
